UNITED STATES PATENT OFFICE.

RICHARD L. MOULTON, OF PROVIDENCE, RHODE ISLAND

AUTOMATIC TRAIN-STOPPING DEVICE.

1,100,390.

Specification of Letters Patent. Patented June 16, 1914.

Application filed March 6, 1913. Serial No. 752,330.

To all whom it may concern:

Be it known that I, RICHARD L. MOULTON, a citizen of the United States, residing at Providence, in the county of Providence and 5 State of Rhode Island, have invented a new and useful Improvement in Automatic Train-Stopping Devices, of which the following is a specification.

This invention relates to an automatic 10 train stopping device, and the object of the invention is to provide novel and improved means for automatically venting the air brake system of the train upon the setting of tripping means to operative position.

15 A further object of the invention is to provide novel and improved tripping means for the air brake system venting means, and to otherwise generally improve, simplify and increase the efficiency of the several 20 aforementioned means.

In the drawings—Figure 1 is a perspective view of the invention showing the parts in relative positions on the track and locomotive, the latter parts being shown in fragment. Fig. 2 is an end elevation of the 25 means for operating the air brake. Fig. 3 is a fragmentary side elevation of Fig. 2 parts being broken away, and shown in section. Fig. 4 is a side elevation of the air 30 brake venting valve. Fig. 5 is a section on the line 5—5 of Fig. 4. Fig. 6 is a front elevation of the tripping means, and Fig. 7 is an end elevation of Fig. 6.

The tripping means consists of a support- 35 ing frame that includes a pair of end mem- bers 1 which are centrally depressed at 2, the ends of the members being suitably at- tached to the under faces of two or more of the track ties. A transverse plate 3 is se- 40 cured at its ends to the depressed parts 2 of the end members 1, and an arched member 4 overlies the plate 3 and has its ends secured to the latter. Secured to the top of the arched member 4 at the ends of said top, 45 are a pair of transverse bars 5 which have one of their ends extending beyond the ad- jacent side of the member 4 and formed with rounded extremities that provide pivots for the arms 6 and 7 respectively, the arms hav- 50 ing brackets 8 bolted thereto, which brackets are perforated to receive the rounded ex- tremities of the bars 5. The arm 6 has a bracket 9 attached to its lower end, while the arm 7 has a similar bracket 10 attached 55 to its upper end, a diagonal bar 11 being pivoted at its ends to the horizontal arms 12,

formed on said brackets, whereby the arms 6 and 7 are connected to move in unison. Attached to the bracket 9 is an inclined plate 13 to which latter is connected a wire 60 or rod 14. The arm 7 has its lower end portion extended horizontally at 15 and then extended downwardly at 16, the extremity of the end 16 being connected to a wire or rod 17. The wires 14 and 17 may be connected to the signal operating levers, or they may be in connection with the operating mechanism of the signal tower, the wire 17 being for the purpose of moving the parts to inoperative position, while the wire 14 65 has for its purpose the moving of the parts to operative position. In order to rigidly hold the arms in operative position, a latch is provided which consists of a member 18, which is attached to the plate 3 and which 70 is formed with an outstanding arm 19 that has a right angular end 20 adapted to en- gage the arm 6 when the latter is in oper- 75 ative position depicted in Fig. 6 of the drawings. A bracket 21 is rigidly secured to the plate 3 and has a guide finger 22 which 80 engages the end 16 of arm 7 and prevents any tendency the same may have to move laterally when said arm is in inoperative position.

85 The venting means for the air brake sys- tem includes a valve 23 rotatably mounted in a casing 24 which latter has a port 25 that is in communication with the pipe 26 of the air system, the valve having a series of ports 90 which when brought to register with the port 25, allow the air to escape through an outlet port 28 formed in the casing 24. The casing 24 is mounted at 30 from a bracket 29 which latter is connected by end members 95 29' to the locomotive frame. The ends of the valve are provided with portions 31 of square cross-section which latter are received in apertures of corresponding shape that are formed in the substantially diamond 100 shaped arms 32. The arms 32 are secured to the ends 31 of the valve by means of collars 33. The arms 32 are inclined outwardly 105 away from each other, at their lower ends and are connected by means of a cross rod 34.

The bracket 29 is provided with end mem- bers 35 which have downwardly extending extremities 36 that are slotted to receive the arms 32. Latching devices 37 are attached to the parts 36, as shown in Figs. 2 and 3 110 in order to hold the arms 32 in raised posi- tion after actuation of the latter.

- In operation the arms 6 and 7 are moved to raised position by movement of the wire 14, and in this position should a train attempt to pass the arms, the cross rod 34 will 5 contact with said arms and will be moved upwardly, carrying with it the arms 32, which latter will be engaged with, and held in locked position by the latching devices 37. The stated movement of the arm 32 causes 10 the valve 23 to be moved to venting position, with the result that the air brakes will be set and the train brought to a stop. It will furthermore be seen that each of the operating cables or rods 14 and 17 extend out from 15 same side of the frame 1, and that the arms 6 and 7 are movable laterally of the track.
- Having thus described my invention, I claim as new and desire to secure by Letters Patent;—
- 20 1. In a device of the type set forth, a frame, including end members having central depressed portions, a transverse plate connected to said depressed portions, an arched member secured at its ends to said 25 plate, a pair of arms pivoted intermediate

their ends to the top of said arched member, a diagonal rod pivoted to the top end of one arm and to the lower end of the other arm, an operating wire connected to the lower end of the last named arm, the first named 30 arm having its lower end portion provided with a horizontal portion that terminates in a downturned part, and an operating wire connected to said downturned part.

2. In a device of the type set forth, a 35 frame, a pair of arms pivoted intermediate their ends thereto, a diagonal arm pivoted at its upper end to one of said pair of arms above the pivotal point thereof and pivoted at its lower end to the other of said pair of 40 arms below the pivotal point of said other arm, and operating means for the arms.

In testimony whereof I have signed my name to this specification in the presence of two subscribing witnesses.

RICHARD L. MOULTON.
